UNITED STATES PATENT OFFICE.

WALTER LOWE, OF NOTTINGHAM, ENGLAND, ASSIGNOR TO THE KURSHEEDT MANUFACTURING COMPANY, OF NEW YORK, N. Y.

DESIGN FOR PLAITED FABRIC.

SPECIFICATION forming part of Design No. 29,723, dated November 22, 1898.

Application filed August 8, 1898. Serial No. 688,113. Term of patent 7 years.

To all whom it may concern:

Be it known that I, WALTER LOWE, a resident of the city of Nottingham, England, have invented and produced a new and original

5 Design for a Plaited Fabric, of which the following is a specification, reference being had to the accompanying drawing, which is a view in perspective of a piece of plaited fabric embodying my new design.

10 The essential feature of my design consists of a combination of plain accordion plaits *a* and undulated or waved accordion plaits *b*,

the aforesaid plain accordion plaits being so arranged as to form geometrical figures *c*, which figures are surrounded by the undulating accordion plaits.

I claim—

The design for a plaited fabric, substantially as herein shown and described.

WALTER LOWE.
